VALVE CLOSURE

Filed Aug. 4, 1930

INVENTOR.

Maurice C. Tetley.

Harry De Wallace.

ATTORNEY.

UNITED STATES PATENT OFFICE

MAURICE C. TETLEY, OF SYRACUSE, NEW YORK

VALVE CLOSURE

Application filed August 4, 1930. Serial No. 472,966.

This invention relates to collapsible tubes such as commonly employed for tooth paste, shaving cream, and various other liquid and viscous materials, and has for its object to 5 provide novel construction and arrangement of the dispensing means, which may be detachably applied to the usual threaded necks of the tube, to obviate the unscrewing, removing and replacing of the threaded caps 10 or closures. A further object is to provide a dispensing attachment which comprises a substantially circular or disc-like body, having a threaded opening to receive the neck of the tube, said opening preferably being 15 disposed eccentric to the axis of the disc, and being screwed on until the parts are tightly joined. A further object is to provide an inverted cup-shaped member, whose cylindrical portion telescopes the said disc and is 20 rotatable thereon, the closed end of said member being formed with a perforation that is disposed eccentric to its own axis, as well as that of the disc, and which may be rotated in either direction upon said body to 25 bring the said perforation into coincidence with the bore of the neck of the tube, to afford the free dispensing or oozing of the contents of the tube when pressure is exerted to collapse the tube. And a further object is to provide means to connect the said 30 member and disc for swivel action and to prevent accidental separation of said part.

I attain these objects by the detailed description which follows, and as illustrated 35 by the accompanying drawings, in which—

Figure 1 is a top end view of a tube to which my improvement is applied, the dispensing cap being in the "off" position. Fig. 2 is a side elevation of the same. Fig. 3 is 40 a similar end view, the cap being in position to dispense contents of the tube. Fig. 4 is a partial side elevation and partial central vertical section of the device, shown in Fig. 3. Figs. 5 and 6 are respectively, a top 45 end view, and an edge view, taken in the direction of the arrow in Fig. 2. Fig. 7 is a top plan view, showing slight modifications of the disc and cap. And Fig. 8 is a side elevation and partial central vertical section.

50 In the drawings, 2 represents a collapsible

tube, or like container, having a closed bottom 2', and a crowned top 2a, the latter being formed with a bored, externally threaded neck 2c, by which the contents of the tube may be ejected by squeezing the body of the tube. My improved dispensing means, which is designed to take the place of the usual screw caps common to tubes of this class, consists of a relatively thick disc 3, which is formed with an eccentric threaded opening 3' to receive the neck 2c, the depth of the disc preferably corresponding to the height of the said neck. The control for the discharge of the contents of the tube comprises an inverted cup-shaped cap or member 4, whose cylindrical portion 4' loosely telescopes the disc and is manually rotatable thereon. The cap 4 may be rendered inseparable from the disc by folding its lower edge inwardly, as shown in Fig. 4, and for this purpose, the lower corner of the disc may be rabbeted, as at 3a. The top or closed end of cap 4 is formed with an opening 4a, which is preferably disposed eccentric to the axis of the cap and disc 3, and is adapted when the cap is rotated on the disc, to be brought into coincidence with the bore of the neck 2c, to enable the contents of the tube to be dispensed. Following each dispensing operation, the operator should again rotate the cap sufficiently to close the opening in the neck 2c. In practice, the disc 3, with the cap attached, is usually screwed on to the neck, as 2c, of a container having right-hand threads, for example, and in applying the disc, the latter is rotated towards the right 55 until it stops. Thereafter, until the tube is emptied, the cap should be turned towards the right both to open and close the bore of the neck. This tends to prevent the unscrewing and detachment of the disc from the tube.

In Figs. 7 and 8, is shown modified swivel means, which consists of forming a continuous socket or groove, as 3c, in the periphery of the disc, and after the cap 4 is applied, the opposite walls of the barrel are formed with inwardly facing teats, as 4c, to engage said groove. This arrangement allows the cap to be freely rotated on the disc, and obviates all danger of the cap being distorted or detached.

Obviously, by some slight modifications, 100

my improved dispensing mechanism may be applied to many different containers, without departing from the spirit of my invention, as clearly pointed out in the claims.

5 Having thus described my invention, what I claim, is—

1. A valve closure for collapsible tubes including a disk having a threaded opening to receive the threaded discharge neck of the 10 tube, a cap disposed over and about the periphery of the disk and having an eccentric discharge opening, and means to connect the cap to the disk for rotation about the latter, said threaded opening of the disk being disposed eccentrically of the latter, whereby in 15 one position of the cap to cause the discharge opening thereof to register with the discharge neck of the tube and in a second position to lie out of register with said discharge neck 20 thereby to close the latter.

2. A valve closure for collapsible tubes composed of means having an opening to receive the discharge neck of the tube therein, valve means disposed over and about the 25 periphery of the first named means and being rotatable relative thereto and having an eccentric discharge opening, and means to connect the valve means to the first named means for rotation, said opening of the first 30 named means being eccentrically related thereto whereby the discharge opening of the valve member in one position registers with the discharge neck of the tube and in a second position is out of register therewith so as 35 to close same.

In testimony whereof I affix my signature.
MAURICE C. TETLEY.
